UNITED STATES PATENT OFFICE.

JOSEPH WHITE, OF PISCATAWAY TOWNSHIP, MIDDLESEX COUNTY, NEW JERSEY,
ASSIGNOR TO HALL PRINTING PRESS COMPANY, OF DUNELLEN, NEW JERSEY, A
CORPORATION OF NEW JERSEY.

SHEET-DELIVERY MECHANISM.

1,080,036.

Specification of Letters Patent.

Patented Dec. 2, 1913.

Application filed October 28, 1910. Serial No. 589,627.

To all whom it may concern:

Be it known that I, JOSEPH WHITE, a citizen of the United States, residing in Piscataway township, county of Middlesex, 5 State of New Jersey, have invented certain new and useful Improvements in Sheet-Delivery Mechanism.

In the accompanying drawings, I have illustrated one form of my novel devices 10 in a delivery mechanism which consists of an endless carrier for a pair of gripper bars which engage the forward end of the sheet, taking it from the gripper mechanism of the impression cylinder and carrying it forward over and allowing it to drop on the delivery pile. Where a carrier of this description is employed, the sheets are apt to drop irregularly, especially when the machine is run at a high speed, making an 15 uneven pile, but I have found that by stretching the sheet over the delivery pile while it is in control of the carrier, and retarding its motion from behind and allowing the final movement of the sheet to be 20 effected from the tail, the sheets will be delivered on the delivery pile with great accuracy and in smooth condition.

Referring to the drawings:—Figure 1 is an elevation of so much of the machine as is 30 required to illustrate the invention in the form which I have chosen for purposes of illustration. Fig. 2 is a plan view of Fig. 1.

1 and 2 represent the side frames of the machine in which is mounted the impression 35 cylinder 3, in which is mounted the usual gripper shaft 4 having its set of sheet-taking grippers 5. On the end of said shaft is fastened the usual tumbler 6 which is rocked by the usual tumbler pins to open and close 40 the grippers.

As this invention relates to the delivery part of the machine, the opening tumbler pin 7 only is shown. In the forward rotation of the impression cylinder the tumbler 6 45 strikes the tumbler pin 7 and rocks the shaft 4, causing the grippers to open and release the sheet.

Fastened to the impression cylinder 3 is a driving gear 8 which meshes with a gear 50 9 fastened to the sprocket shaft 10, said shaft being mounted in the side frames of the machine. This sprocket shaft has a pair of driving sprockets 11 and 12 fastened to it, over which runs a pair of end-

less chains 13 and 14. These chains also 55 pass over another pair of sprockets 25 and 26 mounted on studs 27 in the side frame of the machine, said studs being adjustable in slots 28, by which means the chains are given their proper tension. The length of 60 the chain being equal to twice the periphery of the impression cylinder, two sets of grippers are mounted thereon in order to take a sheet from the impression cylinder every 65 revolution.

The bar supporting links on the chain consist of plates 15 to which is rigidly fastened rod 16 and in which is journaled gripper shaft 17. The rods 16 have formed on them gripper blocks 18 against which 70 the grippers 19 act to nip the sheets. The gripper shaft 17 has mounted on it torsion springs 20 which tend to close the grippers against the gripper blocks.

Fastened to the gripper shafts are levers 75 21 which hold cam rollers 22 which act upon the cam 23 as it is carried forward which cause the delivery grippers to open and close to take the sheet from the impression cylinder grippers, and on the other end of 80 its movement as the roller passes over the cam 24, the grippers are opened, allowing the sheets to drop on a pile in a manner to be hereinafter described.

While the method of retarding the tail of 85 the sheet and applying tension to the same for the purpose of stretching it while in control of the grippers may be varied widely, the preferred form in the type of machine illustrated consists of a pair of retarding 90 rollers controlled and operated in the following manner: Journaled in the side frames just behind the delivery board and below the delivery chains and the path of the delivery grippers, is a retarding roller 30. It 95 will be seen that in the forward movement of the sheets while they are being delivered, the sheets will be drawn over this roller. Fastened to pulley 33 loosely mounted on the end of roller 30 is an arm 34, which carries a pawl 35 which engages a ratchet 36, said ratchet being fastened to the retarding roller 30. Pulley 31 is attached to the shaft of the cylinder 3 and the belt 32 connects pulleys 31 and 33, these pulleys being so proportioned that the surface of the roller 30 has a slower speed than the speed of the 100 surface of cylinder 3 or of the grippers 19.

Coacting with retarding roller 30 are a pair of retarding wheels 37 which are mounted each upon an arm 38 adjustably fastened upon a rockshaft 39 located between the upper and lower path of the delivery chains. 5 Fastened to one end of this rockshaft 39 is an arm 40 to which is pivoted a connection 41, the other end of which is connected to arm 42 formed on a hub 43 loosely pivoted 10 on a stud 44 fastened in the side frame of the machine. This hub 43 has another arm 45 formed on it, one end of which carries a roller 46 which runs upon a cam 47, said cam being adjustably fastened to the end 15 of the impression cylinder.

By means of the connections and parts previously mentioned, it can be seen that the retarding wheels 37 will be moved into and out of contact with the retarding roller 30, and that the sheets to be delivered passing between the retarding roller and the wheels will be nipped, and as they are moving at a slower speed than the sheet or the grippers 19, the sheet will be stretched between the grippers holding the forward end 20 and the retarding rollers acting upon the rear end. This cam 47 is so formed as to cause the wheels to rise in time to clear the grippers and gripper bars as they pass under it, and to lower onto the tail of the sheet 25 in the proper position and engage said sheet between the retarding roller and the wheels so as to draw it in tension before it is completely over the delivery pile. After the 30 sheet has been in tension, it is generally desirable to cause the grippers to release the sheet and to allow the retarding roller and wheel to complete the last of the movement in delivering the sheet: although in cases 35 where the sheet is very light weight, the grippers will be caused to retain the sheet a longer time than with a heavier weight sheet.

In order to control the point of travel at 40 which the grippers will release the sheet, the cam 24 is made adjustable; said cam being adjustable and mounted on a cam plate 48, said cam plate being fastened on the end of the studs 24.

The cam 47 which controls the point at 45 which the sheet is nipped by the roller 37 is also made adjustable and is fastened to the cylinder end by a bolt 49 at its center and another bolt 50 which passes through the 50 slot 51 formed in the cam. It will be seen that the peripheral speed of roller 30 is slower than the speed of the sheet which is moving over it, and that when the wheel 37 comes in contact with the sheet, the speed of 55 the roller 30 tends to be accelerated by the sheet after it has been drawn taut. The pawl 35 and ratchet 36 allow this acceleration to be accomplished. After the sheet has been drawn taut the grippers are opened 60 and the final movement in depositing the 65

sheet is given by the rollers. I have also found that in certain cases the mechanism is more efficient where the belt 32 is removed from the pulleys and the sheet is nipped between the undriven rollers. In this case, 70 tension is imparted to the sheet and it is stretched out flat over the delivery pile, in overcoming the inertia of the nipping rollers 30 and 37, while the sheet is being drawn through them by the grippers. When the 75 sheet is drawn taut, it starts the rollers rotating with it and after the grippers release the sheet, this rotation of the rollers is sufficient to effect the last of the delivery movement of the sheet and to deposit it properly 80 in the delivery pile. With this arrangement, the nipping rollers obviously can have no greater than, and generally not so great a surface speed, as the sheet at the time the grippers release the sheet, and as soon as 85 the release takes place, the friction of the bearings is sufficient to set up a retardation of the rollers and of the sheet, while at the same time enough energy is stored in the rollers to deliver the tail of the sheet. 90

What I claim is:

1. In a sheet delivery mechanism, a carrier, sheet taking means on said carrier adapted and arranged to engage the front edge of the sheet and carry it over the delivery pile and retarding means adapted and arranged to engage and retard the tail of the sheet while the front edge is engaged by said sheet taking means, said sheet taking means and said retarding means being arranged to co-act to stretch the sheet longitudinally before said sheet taking means is disengaged from the sheet. 95

2. In a sheet delivery mechanism, a carrier, sheet taking means on said carrier adapted and arranged to engage the front edge of the sheet and carry it over the delivery pile and retarding means located behind the delivery pile and adapted and arranged to engage and retard the tail end of 100 the sheet while the front edge is engaged by said sheet taking means, said sheet taking means and said retarding means being arranged to co-act to stretch the sheet longitudinally before said sheet taking means is 105 disengaged from the sheet.

3. In a sheet delivery mechanism, a carrier, sheet taking means on said carrier adapted and arranged to engage the front edge of the sheet and carry it over the delivery pile, and a pair of rollers located at the rear of the pile and adapted and arranged to engage and retard the tail of the sheet while the front edge is engaged by 110 said sheet taking means. 115

4. In a sheet delivery mechanism, a carrier consisting of a pair of endless chains and gripper bars mounted between them; sheet taking means comprising a set of grippers mounted on said bars, a roller located 120 125

below the path of said gripper bars, a coacting movably mounted roller above said roller and means for moving said movably mounted roller into and out of the path of the 5 gripper bars, and into and out of engagement with the sheet to retard the tail thereof while it is being carried over the delivery pile by said grippers.

5. In a sheet delivery mechanism, a carrier, a set of grippers mounted on said carrier for engaging the front edge of the sheet to carry it over the delivery pile, sheet retarding means adapted to engage the sheet while it is held in said grippers and arranged 10 to stretch the sheet by resisting the pull of said grippers, and means for opening the grippers while the sheet is in control of the retarding means.

6. In a sheet delivery mechanism, a carrier, a set of grippers mounted on said carrier arranged to engage the forward end of the sheet to carry it over the delivery pile, a pair of rollers arranged to engage the tail of the sheet, means for moving one roller 15 into and out of contact with the other, means whereby the point of release of the grippers may be varied, and means whereby the point of engagement of the rollers with the sheet may be varied.

20 7. In a sheet delivery mechanism, a carrier, means for moving said carrier at a uniform speed, sheet taking means on said carrier and a continuously rotating retarding member constructed and arranged to frictionally engage the sheet while it is held by said sheet taking means.

8. In a sheet delivery mechanism, a carrier, sheet taking means on said carrier, a continuously moving member adapted to 25 frictionally engage the sheet and driving means adapted and arranged to move the engaging surface of said member at a speed slower than the speed of said sheet taking means, said driving means including a slip 30 device adapted and arranged to permit said engaging surface to be moved at a faster speed than that given it by said driving means.

45 9. In a sheet delivery mechanism, a sheet retarding device comprising a pair of contacting rollers adapted to engage respectively the upper and the lower surfaces of the sheet, driving means for said rollers and means to draw a sheet through said rollers 50 at a speed greater than that of the periphery of said rollers when driven by said driving means, said driving means including a slip device adapted and arranged to permit said rollers to be rotated at a faster speed than that given them by said driving means.

60 10. In a sheet delivery mechanism, a carrier, sheet taking means on said carrier

adapted and arranged to engage the forward end of the sheet and carry it in a forward direction, rotatable retarding means 65 adapted and arranged to engage the tail of the sheet, said sheet taking means and said retarding means being arranged to co-act to stretch the sheet longitudinally before said sheet taking means is disengaged from 70 the sheet, means to operate the engaging means to release the forward end of the sheet while it is engaged by the retarding means, said retarding means being adapted and arranged to progress the sheet forwardly, but at a slower speed than that given it by the said carrier.

75 11. In a sheet delivery mechanism, sheet retarding rollers and a carrier adapted and arranged to engage the sheet and pass it 80 between said rollers and to release it while it is engaged by said rollers, said rollers being adapted and arranged to move the sheet after its release by the carrier and in the same direction but at a slower speed 85 than that given by the carrier.

12. In a sheet delivery mechanism, a pair of contacting rollers and a carrier adapted and arranged to engage the sheet and pass it between said rollers and to release it while 90 it is engaged by said rollers, said rollers being adapted and arranged to rotate after such release to progress the sheet in the same direction as that given by the carrier.

95 13. In a sheet delivery mechanism, a carrier, a set of grippers mounted on said carrier arranged to engage the forward end of the sheet to carry it over the delivery pile, a pair of rollers arranged to engage the tail of the sheet, means for moving one roller 100 into and out of contact with the other and means whereby the point of engagement of the rollers with the sheet may be varied.

14. In a sheet delivery mechanism, a carrier, means for moving said carrier at a uniform speed, sheet taking means on said carrier and a rotatable retarding member constructed and arranged to engage the sheet 105 frictionally while it is held by said sheet taking means.

110 15. In a sheet delivery mechanism, a carrier, means for moving said carrier at a uniform speed, sheet taking means on said carrier, a movably mounted rotatable retarding member and means to bring said member 115 into frictional engagement with the sheet while it is held by said sheet taking means.

In witness whereof I have hereunto set my hand in the presence of two subscribing witnesses.

JOSEPH WHITE.
